RAILWAY TRAFFIC CONTROLLING APPARATUS

Vene P. Shepardson, Belview Heights, Ala., assignor to The Union Switch and Signal Company, Swissvale, Pa., a corporation of Pennsylvania

Application June 23, 1943, Serial No. 491,880

7 Claims. (Cl. 246-22)

My invention relates to railway traffic controlling apparatus, and particularly to apparatus for effecting control of an approach indication device in a given direction over a pair of conductors, that is, from a given end of a pair of conductors to the other, and for then effecting control of a signal in the opposite direction over the same pair of conductors.

In interlocking plants of either the manually controlled type or the automatically controlled type, it has been common practice to control approach indication relays over given line conductors and to control the corresponding distant signals over different line conductors or over the track rails.

One feature of my invention is the provision of an approach indication circuit normally energized over the rails of the track section into which a distant signal governs traffic movements, and the provision of a circuit which can become energized either manually or automatically over the rails of the same track section for clearing the distant signal after the approach indication circuit becomes deenergized by a train approaching the distant signal.

I shall describe two forms of apparatus embodying my invention, and shall then point out the novel features thereof in claims.

In the accompanying drawing, Fig. 1 is a diagrammatic view showing one form of apparatus embodying my invention in which a two-indication signal is controlled by a neutral circuit; and Fig. 2 is a diagrammatic view showing a modified form of the apparatus of Fig. 1 in which polarized control of a three-indication signal is provided.

Similar reference characters refer to similar parts in each of the views.

Referring first to Fig. 1, a stretch of railway track is shown, over which traffic movements are normally made in the direction indicated by the arrow, which I shall assume is the eastbound direction. This stretch of track is divided by insulated joints 2 into section OIT, IDT and IT. Each of the sections OIT and IT is provided with a track circuit including a suitable source of current, such as a battery 3, connected across the rails adjacent one end of the section, and a track relay, designated by the reference character R with a distinguishing prefix corresponding to the prefix for the reference character T for the same track section, connected across the rails adjacent the opposite end of the section.

A home signal 1 is shown adjacent the entrance end of section IT for governing traffic movements into that section, and a distant signal 1D is shown adjacent the entrance end of section IDT for governing traffic movements into section IDT. As here shown, signal 1 is of the two-indication color light type, comprising a

green or proceed lamp G and a red or stop lamp R. Signal 1D is also of the two-indication color light type, comprising a green or proceed lamp G and a yellow or caution lamp Y. These signals may, however, be of any other suitable type.

Section OIT serves as an approach section for signal 1D, and track relay OIR may therefore be termed an approached relay.

An approach control relay AR is normally energized by a circuit including front contacts of approach relay OIR, and including the rails of track section IDT, and also including back contacts of a home signal relay IH which controls signal 1.

Only portions of two control circuits for relay IH are shown, one of which includes a back contact of relay AR, and the other of which includes a normally open contact 14 of a manual control lever V, and both of which include contact 15 of track relay IR. Lever V has a normal position *n*, in which it is shown in the drawing, and a reverse position *r* to which it is moved to close contact 14.

Relay IH, upon becoming energized by either of these control circuits, closes its contacts 1 and 8 at their front points, and hence a distant signal relay IDH, for controlling signal 1D, will become energized over a circuit including the rails of section IDT, if relay OIR is deenergized, or when it becomes deenergized due to the presence of a train on section OIT.

An approach indication device, here shown as a lamp AK, is controlled by a back contact of relay AR.

In Fig. 2, the apparatus differs from that shown in Fig. 1 in the control of signal 1D which is here a three-indication signal. Relay IDH is here a polarized relay controlled by circuits of normal and reverse polarities, each including the rails of section IDT.

With relay IH deenergized, relay IDH can become energized by its reverse control circuit which includes back contacts of each of the relays AR, IH and OIR. An asymmetric unit *t*, which can be of the well-known copper oxide half-wave rectifier type, opposes the flow of current from this reverse control circuit through relay AR, thereby preventing energization of relay AR by the reverse control circuit for relay IDH. The normal control circuit for relay IDH includes front points of contacts 1 and 8 of relay IH, which thereby serve as pole changers, and the back points of contacts of relay OIR.

As shown in the drawing, all parts are in the normal condition, that is, lamp R of signal 1 is lighted, and the lamps of signal 1D are unlighted; relays OIR, IR, and AR are energized; relays IH and IDH are deenergized; lever V is in its normal position *n*; and indication lamp AK is unlighted.

I shall now describe more in detail the operation of the apparatus shown in Fig. 1. The circuit by which relay AR is normally energized passes from a source of current, such as a battery 4, through the front point of contact 5 of relay OIR, rail 6 of section IDT, the back point of contact 7 of relay IH, winding of relay AR, back point of contact 8 of relay IH, rail 9 of section IDT, and the front point of contact 10 of relay OIR back to battery 4. The circuit by which lamp R of signal 1 is lighted passes from terminal B, through the back point of contact 11 of relay IH, and lamp R to terminal O.

I shall assume that an eastbound train enters section OIT, deenergizing relay OIR. The circuit previously traced for relay AR is therefore disconnected from battery 4 at contacts 5 and 10 of relay OIR, causing relay AR to become deenergized. With relay AR deenergized, indication lamp AK is lighted by a circuit passing from terminal B, through contact 12 of relay AR, and lamp AK to terminal O.

Also, with relay AR deenergized, relay IH will become energized by its circuit which includes the back point of contact 13 of relay AR, and contact 15 of relay IR. Relay IH, upon becoming energized, opens, at the back point of its contact 11, the circuit previously traced for lamp R of signal 1, and closes, at the front point of contact 11, the circuit for lighting lamp G of signal 1.

With relay IH energized and relay OIR deenergized, a circuit is completed for energizing relay IDH, this circuit passing from a suitable source of current such as a battery 16, through the front point of contact 7 of relay IH, rail 6 of section IDT, back point of contact 5 of relay OIR, winding of relay IDH, back point of contact 10 of relay OIR, rail 9 of section IDT, and the front point of contact 8 of relay IH back to battery 16. With relay IDH now energized while relay OIR is deenergized, a circuit is completed for lighting lamp G of signal ID, this circuit passing from terminal B, through contact 17 of relay OIR, front point of contact 18 of relay IDH, and lamp G of signal ID to terminal O.

When the train enters section IDT, the circuit previously traced for relay IDH will be shunted by the wheels and axles of the train across rails 6 and 9 of section IDT, and hence relay IDH will become deenergized, causing lamp G to become extinguished, and causing lamp Y to become lighted by a circuit passing from terminal B, through contact 17 of relay OIR, back point of contact 18 of relay IDH, and lamp Y of signal ID to terminal O.

When the train leaves section OIT, contact 17 of relay OIR will open, thereby extinguishing lamp Y of signal ID. Relay OIR, upon becoming energized, closes its contacts 5 and 10 at their front points, as in the normal condition of the apparatus.

The train, upon entering section IT, will deenergize relay IR, contact 15 of which will thereupon open the circuit for relay IH. Lamp R of signal 1 will therefore again become lighted.

When the train leaves section IDT, thereby removing the shunt from rails 6 and 9 of section IDT, relay AR will become energized by its circuit previously traced. Indication lamp AK will therefore become extinguished.

In the form of apparatus shown in Fig. 2, the circuit by which relay AR is normally energized is the same as was traced in connection with

Fig. 1, except that it includes the asymmetric unit t in its low resistance direction.

With the apparatus shown in Fig. 2, I shall assume that a train enters section OIT, thereupon deenergizing relay OIR. Lamp R of signal ID will therefore be lighted by a circuit passing from terminal B, through contact 17 of relay OIR, back point of contact 18 of relay IDH, and lamp R of signal ID to terminal O. With relay OIR deenergized, the circuit for relay AR will be disconnected from battery 4 at contacts 5 and 10 of relay OIR, and hence relay AR will become deenergized.

If section IT is now occupied, or if relay IH cannot become energized for some other reason, relay IDH will now become energized in the reverse direction by a circuit passing from battery 16, through contact 20 of relay AR, back point of contact 8 of relay IH, rail 9 of section IDT, back point of contact 10 of relay OIR, winding of relay IDH, back point of contact 5 of relay OIR, rail 6 of section IDT, back point of contact 7 of relay IH, and contact 21 of relay AR back to battery 16. Lamp Y of signal ID will therefore become energized by a circuit passing from terminal B, through contact 17 of relay OIR, front point of contact 18 of relay IDH, contact 19 of relay IDH closed in the right-hand position, and lamp Y of signal ID to terminal O.

If, on the other hand, relay IH is energized while a train occupies section OIT, relay IDH will become energized in the normal direction by a circuit passing from battery 16, through the front point of contact 7 of relay IH, rail 6 of section IDT, back point of contact 5 of relay OIR, winding of relay IDH, back point of contact 10 of relay OIR, rail 9 of section IDT, and the front point of contact 8 of relay IH back to battery 16. With relay IDH energized by current of normal polarity, lamp G of signal ID will become lighted by a circuit passing from terminal B, through contact 17 of relay OIR, front point of contact 18 of relay IDH, contact 19 of relay IDH closed in the left-hand position, and lamp G of signal ID to terminal O.

When the train enters section IDT, thereby shunting the circuit for relay IDH at rails 6 and 9 of section IDT, relay IDH will become deenergized, thereupon again completing the circuit previously traced for lamp R of signal ID.

When the train leaves section IDT, relay AR will again become energized by its circuit including asymmetric unit t.

Although I have herein shown and described only two forms of apparatus embodying my invention, it is understood that various changes and modifications may be made therein, within the scope of the appended claims without departing from the spirit and scope of my invention.

Having thus described my invention, what I claim is:

1. In control means for a home signal and for a distant signal for said home signal, including a track section between said home and distant signals, including an approach track relay for an approach track section which adjoins said first track section at a point adjacent said distant signal, including a signal relay for controlling said home signal, the combination comprising, an approach control relay, a track circuit including the rails of said track section between said home and distant signals and including front and back contacts of said approach track relay and said signal relay respectively for controlling said approach

control relay, a back contact of said approach control relay included in a circuit for controlling said signal relay, a distant relay for controlling said distant signal, and a circuit including the rails of said track section between said home and distant signals and including front and back contacts of said signal relay and said approach track relay respectively for controlling said distant relay.

2. In an approach indication and signal control scheme for a given signal including a first track section into which traffic movements are governed by said given signal, including an approach track section through which traffic movements are made before passing said signal into said first section, including a normally energized approach relay which becomes deenergized in response to a train entering said approach track section, and including a signal relay for controlling said signal, the combination comprising, a manually controllable relay, an approach indication device, a circuit including the rails of said first track section and controlled by a front contact of said approach relay and by a back contact of said manually controllable relay for controlling said approach indication device, and a second circuit including the rails of said first track section and controlled by a back contact of said approach relay and by a front contact of said manually controllable relay for controlling said signal relay.

3. In an approach indication and signal control scheme for a given signal including a first track section into which traffic movements are governed by said given signal, including an approach track section through which traffic movements are made before passing said signal into said first section, including a normally energized approach relay which becomes deenergized in response to a train entering said approach track section, and including a signal relay for controlling said signal, the combination comprising, an approach control relay, a second signal relay controlled in part by a back contact of said approach control relay, a circuit including the rails of said first track section and controlled by a front contact of said approach relay and by a back contact of said second signal relay for controlling said first signal relay.

4. In an approach indication and signal control scheme for a given signal including a first track section into which traffic movements are governed by said given signal, including an approach track section through which traffic movements are made before passing said signal into said first section, including a normally energized approach relay which becomes deenergized in response to a train entering said approach track section, and including a signal relay and means for at times energizing said signal relay, the combination comprising, an approach indication device, a circuit controlled by a front contact of said approach relay and by a back contact of said signal relay for controlling said approach indication device, and a second circuit controlled by a back contact of said approach relay and by a front contact of said signal relay for controlling said signal relay for controlling said signal.

5. In an approach indication and signal control scheme for a given signal including a first track section into which traffic movements are governed

by said given signal, including an approach track section through which traffic movements are made before passing said signal into said first section, including a normally energized approach relay which becomes deenergized in response to a train entering said approach track section, and including a signal relay and means for at times energizing said signal relay, the combination comprising, an approach indication device, a circuit controlled by traffic conditions in said first track section and by a front contact of said approach relay and also by a back contact of said signal relay for controlling said approach indication device, and a second circuit controlled by traffic conditions in said first track section and by a back contact of said approach relay and by a front contact of said signal relay for controlling said signal.

6. In an approach indication and signal control scheme for a given signal including a first track section into which traffic movements are governed by said given signal, including an approach track section through which traffic movements are made before passing said signal into said first section, including a normally energized approach relay which becomes deenergized in response to a train entering said approach track section, including a signal relay and means for at times energizing said signal relay, and including an indication relay and indication means controlled by said indication relay, the combination comprising, an asymmetric unit, a circuit including said asymmetric unit and the rails of said first track section and controlled by a front contact of said approach relay and by a back contact of said signal relay for controlling said indication relay, a circuit of a given polarity opposed by said asymmetric unit including the rails of said first track section and controlled by a back contact of each of said relays for controlling said signal, and a circuit of the opposite polarity including the rails of said first track section and controlled by a back contact of said approach relay and by a front contact of said signal relay for also controlling said signal.

7. In a circuit arrangement for controlling a given neutral relay at a given point by current supplied over a given pair of conductors from a remote point and for controlling apparatus at the remote point by current of normal and reverse polarities supplied over the same pair of conductors from said given point, the combination comprising, an asymmetric unit, a pole changer at said given point arranged to be closed in a first or a second position, a control contact at said remote point arranged to be closed in a first or a second position, a circuit including said asymmetric unit and said pair of conductors and including said contact and said pole changer in said first positions for energizing said neutral relay, a circuit of a given polarity opposed by said asymmetric unit including said pair of conductors and including said control contact in its second position and said pole changer in its first position and controlled by a back contact of said neutral relay for controlling said apparatus at said remote point, and a circuit of the opposite polarity including said pair of conductors and including said control contact and said pole changer both in their second positions for also controlling said apparatus at said remote point.

VENE P. SHEPARDSON.
